UNITED STATES PATENT OFFICE.

EDWARD KRONENBERG, OF PHILADELPHIA, PENNSYLVANIA.

LIGHTING DEVICE.

SPECIFICATION forming part of Letters Patent No. 480,500, dated August 9, 1892.

Application filed March 6, 1891. Serial No. 384,035. (No model.)

To all whom it may concern:

Be it known that I, EDWARD KRONENBERG, a citizen of the United States, residing at the city of Philadelphia, in the county of Philadelphia and State of Pennsylvania, have invented certain new and useful Improvements in Lighting Devices, of which the following is a specification.

My present invention relates to that class of lighting devices designated as "pocket-lamps," and provided with a lid or cover, a suitable wick, a strip, tape, or ribbon having pellets, caps, or ignitable material applied thereto, and means for contacting with and exploding the same in order to light the wick.

The principal objects of my present invention are, first, to provide simple, durable, and efficient means adapted to be automatically actuated by the opening and closing of the lid or cover of the device to feed a strip, tape, or ribbon provided with pellets, fulminates, or ignitable material into close proximity with a suitable wick, and, second, to provide means accessible from the exterior of the housing and adapted to release a lid or cover and to actuate a scratcher or ignitor to cause the pellets, fulminates, or ignitable material in proximity to a wick or suitable light-producing appliance to be ignited.

My invention consists of a lighting device comprising a housing provided with a hinged cover, an adjustable oil and wick reservoir, an appliance for feeding and winding upon itself a fulminating tape, strip, or ribbon, an ignitor or scratcher, and devices connected with said cover and feeding appliance and adapted to automatically actuate the latter by the closing of the cover.

My invention further consists of a lighting device provided with a housing having a hinged cover and an extinguisher, an oil and wick reservoir, a feeding appliance winding and holding upon itself a tape, strip, or ribbon containing fulminates or pellets of ignitable material, an ignitor or scratcher, and means for actuating said ignitor or scratcher and for causing said feeding appliance to be rotated.

My invention further consists of a lighting device comprising a housing, a wick, a feeding appliance for winding upon itself a tape, strip, or ribbon having pellets, fulminates, or

ignitable material applied thereto, means for rotating the same, a hand-knob outside of said housing and connected with a scratcher or ignitor adapted to contact with and ignite said pellets, fulminates, or ignitable material.

My invention further consists of a lighting device comprising a housing, a hinged cover, a spring-catch accessible from the exterior of the housing and adapted to engage said cover, a wick, a feeding appliance for winding upon itself a tape, strip, or ribbon having pellets, fulminates, or ignitable material applied thereto, pawl-and-ratchet connections between said cover and feeding device, a hand-knob outside of said housing and adapted to contact with and release said spring-catch, and an ignitor or scratcher connected with said knob, so that when the hand-knob is actuated the cover is thrown open and the wick lighted and when the cover is closed the tape, strip, or ribbon is advanced; and my invention further consists in the improvements hereinafter fully described, and particularly pointed out in the claims.

The nature and objects of my present invention will be more fully understood from the following description, taken in connection with the accompanying drawings, forming part hereof, and in which—

Figure 1 is a perspective view of a lighting device embodying features of my invention and showing a hinged cover and two-part housing in open position, so as to expose to view the parts of the device; and Fig. 2 is a similar view showing the two-part housing in a closed position and showing, also, the upper portion of the hinged lid or cover broken away.

In the drawings the housing *a* comprises two parts *a'* and *a''*, preferably hinged together and provided with a spring-latch *a³*, for retaining the two parts normally in a closed position.

a⁴ is a cover hinged to the part *a'* of the housing and adapted to be automatically opened by means of a spring *a⁵*, attached to the interior of the housing *a* and contacting with the interior of the cover *a⁴*.

a⁶ is a spring-catch adapted to engage the cover *a⁴* when the latter is closed and provided with a lug *a⁷*, extending through a suitable slot formed in the housing *a*, so that

when the stud a^7 is pressed the catch a^6 releases the cover a^4 , whereupon the spring a^5 causes the latter to fly open, as shown in Fig. 1.

5 b is a slightly-curved guide-plate provided with a slot b' and attached to or formed integral with the part a' of the housing. This plate b serves to direct the tape, strip, or ribbon and to support the same during the operation of igniting the pellets, fulminates, or ignitable material, as will be hereinafter more fully described.

d is a wick and oil receptacle attached to the part a^2 of the housing, so that when the housing is in a closed position the wick is in proximity to the guide-plate b , Fig. 2, and when the housing is in an open position the oil-receptacle may be conveniently filled. This wick and oil receptacle d is preferably supported loosely by means of loops d' , attached to the part a^2 of the housing, Fig. 1, and is provided with a stud d^2 , working in the slot in the part a^2 of the housing, so that the receptacle d may be shifted upward in order to cause the lighted wick to project beyond the housing and downward into the housing when the lamp is not in use.

d^3 is a set-screw adapted to engage the stud d^2 in order to clamp the receptacle d to place 30 after it has been adjusted.

d^4 , Fig. 1, is an extinguisher attached to the interior of the cover a^4 and adapted to extinguish the wick when the cover a^4 is closed.

35 e is a roller or other suitable appliance supported by the part a' of the housing and adapted to retain a strip, tape, or ribbon having a supply of pellets, fulminates, or ignitable material x' applied thereto.

40 f is a drum provided with slots f' for engaging the end of the tape, strip, or ribbon x and journaled to the side a' of the housing, so that the strip, tape, or ribbon x is led from the roller e past the guide-plate b and slot b'

45 and is attached to the drum f by passing the end of the tape, strip, or ribbon into the slot f' . This tape, strip, or ribbon x is fed forward by rotating the drum f and winding the strip, tape, or ribbon thereon. The drum f

50 is rotated by means of pawl-and-ratchet connections comprising a ratchet-wheel f^2 , connected with the drum, and a pawl f^3 , actuated by the cover a^4 and adapted to engage the teeth of the ratchet-wheel f^2 . In the drawings this pawl f^3 is represented as pivotally attached to the spring a^5 ; but it will be readily understood that the pawl f^3 could, if preferred, be pivotally attached to the cover a^4 , the object being to cause the cover a^4 in clos-

55 60 ing to push the pawl forward—that is, toward the left in the drawings—so as to rotate the drum f in order to feed the strip x .

f^4 is a projection attached to the pawl f^3 and adapted to engage a pin f^5 on the part a' of the housing, in order to prevent the pawl f^3 from being accidentally turned out of operative position.

g is a rotatable spindle supported in bearings formed in the housing a and guide-plate b . 7c

g' is an arm located outside of the housing and provided with a hand-knob g^2 . This arm g' is attached to the spindle g and serves to rotate the same. Moreover, when the hand-knob g^2 is forced downward the arm g' contacts with and presses the lug a^7 , thus actuating the spring - catch a^6 and releasing the spring-actuated cover a^4 .

g^3 is a scratcher or ignitor keyed or otherwise attached to the spindle g and adapted to contact with and frictionally ignite the pellets, fulminates, or ignitable material x' when the hand-knob g^2 is turned.

g^4 is a spiral spring attached to the housing a and spindle g and adapted to normally 85 maintain the arm g' out of contact with the lug a^7 and the scratcher g^3 out of contact with the pellets, fulminates, or ignitable material x' .

h and h' are stop-pins adapted to limit the 90 movements of the arm g' and attached to the housing a ; but it must be borne in mind that these pins may be located within the housing and that any suitable stopping device may be employed in lieu thereof, the object being 95 to prevent the scratcher or ignitor g^3 from being turned too far in one direction or the other.

In use the wick d^5 , protruding from the oil-receptacle d , may be lighted and the cover a^4 100 opened by the simple operation of pressing the hand-knob g^2 downward. This motion of the hand-knob releases the spring-catch a^6 and causes the scratcher or ignitor to be shifted into contact with and to frictionally 105 ignite one of the pellets or fulminates or the ignitable material x' in close proximity to the wick, whereby the latter is lighted. The receptacle d may then be shifted upward and clamped to place by means of the set-screw 110 d^3 in order to cause the wick to extend outside of the housing, so as to be available for lighting cigars and pipes and other purposes.

The lamp may be extinguished by first releasing the set-screw d^3 and then closing the 115 cover a^4 , whereupon the extinguisher d^4 envelopes and extinguishes the wick and the pawl-and-ratchet connections cause the portion of tape, strip, or ribbon x , containing the exploded pellets, fulminates, or ignitable material, to be wound onto the feeding device f , whereby a fresh or unexploded pellet or fulminate is brought beneath the scratcher or ignitor g^3 and into position for being ignited thereby, when the cover is again opened. 125 When all the pellets, fulminates, or ignitable material on the strip have been ignited, the portion a^2 of the housing may be opened, as illustrated in Fig. 1, and such strip, tape, or ribbon removed and replaced by another strip, 130 tape, or ribbon provided with fresh pellets, fulminates, or ignitable material.

It will be obvious to those skilled in the art to which my invention appertains that modi-

fications may be made in the details. For example, the pawl-and-ratchet connections may be employed in connection with other types of ignitors or scratchers without departing 5 from the spirit of my invention, and hence I do not limit myself to the exact construction illustrated in the drawings; but,

Having thus described the nature and objects of my invention, what I claim as new, 10 and desire to secure by Letters Patent, is—

1. A lighting device consisting of a two-part housing provided with a hinged cover, an adjustable oil and wick reservoir, a reciprocating ignitor or scratcher, a rotatable feeding 15 appliance winding upon itself a fulminating tape, strip, or ribbon, and pawl-and-ratchet connections adapted to automatically actuate said feed appliance in the closing of said cover, substantially as and for the purposes set forth.

2. A lighting device consisting of a two-part housing having a spring-actuated hinged cover, a vertically-adjustable oil and wick reservoir, an oscillating scratcher or ignitor, 25 a rotatable feeding appliance winding upon itself a fulminating or igniting tape, strip, or ribbon, means for retaining said appliance normally in position, and devices between said cover and feeding appliance adapted to 30 rotate the latter by the closing of said cover, substantially as and for the purposes set forth.

3. A lighting device consisting of a two-part housing provided with a spring-actuated hinged cover, an adjustable oil and wick reservoir, 35 a scratcher or ignitor reciprocated by means adapted to open said cover, a rotatable feeding appliance winding upon itself a tape, strip, or ribbon, means for preventing retrograde movement of said feeding appliance, a ratchet-wheel attached to said feeding appliance, a pawl provided with a slot and a pin engaging in said slot for preventing displacement of the pawl, substantially 40 as and for the purposes set forth.

4. A lighting device consisting of a housing, a wick, a rotatable feeding appliance for winding upon itself a tape, strip, or ribbon having pellets, fulminates, or ignitable material applied thereto, means for rotating the 45 same, a hand-knob outside said housing, a scratcher or ignitor connected therewith and adapted to contact with and ignite said pellets, fulminates, or ignitable material, substantially as and for the purposes set forth.

5. A lighting device consisting of a two-part housing, a wick, a rotatable feeding appliance for winding upon itself a tape, strip, or ribbon having pellets, fulminates, or ignitable material applied thereto, means for rotating the same, a guide-plate for directing said tape, strip, or ribbon, a hand-knob outside of 50 said housing, a scratcher or ignitor connected with said hand-knob and adapted to contact with and ignite said pellets, fulminates, or ignitable material, substantially as set forth.

6. A lighting device consisting of a housing, a wick, a rotatable feeding appliance for

winding upon itself a tape, strip, or ribbon having pellets, fulminates, or ignitable material applied thereto, means for rotating the 70 same, a guide-plate for directing said tape, strip, or ribbon, a spindle journaled in said guide-plate and housing, a scratcher or ignitor, and a hand-knob attached to said spindle, substantially as and for the purposes set 75 forth.

7. A lighting device provided with a housing, a spring-actuated cover, a catch for maintaining the same in a closed position, a scratcher for igniting a pellet, fulminate, or ignitable material, an arm connected with said scratcher and adapted to release said catch, and a hand-knob for actuating said arm, substantially as and for the purposes set forth.

8. A lighting device provided with a housing, a spring-actuated cover, a catch for maintaining the same in a closed position and provided with a lug projecting through the housing, a scratcher for igniting a pellet, fulminate, or ignitable material, a spindle connected with said scratcher, an arm provided with a hand-knob and adapted to actuate said scratcher and to contact with said lug, substantially as and for the purposes set forth.

9. A lighting device provided with a housing, 95 a spring-actuated cover, a catch for maintaining the same in a closed position, a scratcher for igniting a pellet, fulminate, or ignitable material, an arm connected with said scratcher and adapted to release said catch, a spring 100 for normally maintaining said arm out of contact with said catch, and a hand-knob for actuating said arm, substantially as and for the purposes set forth.

10. A lighting device comprising a housing, 105 a hinged cover, a spring-catch accessible from the exterior of the housing and adapted to engage said cover, a wick, an appliance for feeding and winding upon itself a tape, strip, or ribbon having pellets, fulminates, or ignitable material applied thereto, pawl-and-ratchet connections between said cover and feeding appliance, an ignitor or scratcher, a hand-knob outside said housing for actuating said scratcher or ignitor and spring-catch, substantially 115 as and for the purposes set forth.

11. A lighting device comprising a housing, a spring-actuated cover hinged thereto, a spring-catch provided with a lug accessible from the exterior of the housing and adapted 120 to engage said cover, a wick, an appliance for feeding and winding upon itself a tape, strip, or ribbon having pellets, fulminates, or ignitable material applied thereto, pawl-and-ratchet connections between said cover and feeding appliances, a guide-plate, a spring-controlled spindle journaled in said housing and guide-plate, a scratcher or ignitor attached to said spindle, an arm connected with said spindle and adapted to contact with said lug, substantially 125 as and for the purposes set forth.

12. A lighting device provided with a two-part housing having a hinged cover, an adjustable oil and wick reservoir, an appliance for

feeding and winding upon itself a fulminating tape, strip, or ribbon, pawl-and-ratchet connections between said cover and feeding appliances, a movable scratcher or ignitor, and an extinguisher adapted upon the closing of said cover to envelop the wick of said reservoir, substantially as and for the purposes set forth.

13. A lighting device provided with a housing having a hinged cover and an extinguisher, an oil and wick reservoir, a feeding appliance winding and holding upon itself a tape, strip, or ribbon containing fulminates or pellets of

ignitable material, an ignitor or scratcher, and means for actuating said ignitor or scratcher 15 and for causing said feeding appliance to be rotated, substantially as and for the purposes set forth.

In witness whereof I have hereunto set my signature in the presence of two subscribing witnesses.

EDWARD KRONENBERG.
